UNITED STATES PATENT OFFICE

CHRISTOPHER M. CORDLEY, OF GREENWICH, CONNECTICUT, ASSIGNOR TO CORDLEY & HAYES, OF NEW YORK, N. Y., A CORPORATION OF NEW YORK

DESIGN FOR A DISPENSER FAUCET

Application filed November 26, 1930. Serial No. 37,790. Term of patent 7 years.

To all whom it may concern:

Be it known that I, CHRISTOPHER M. CORDLEY, a citizen of the United States, residing at Greenwich, in the county of Fairfield and State of Connecticut, have invented a new, original, and ornamental Design for Dispenser Faucet, of which the following is a specification, reference being had to the accompanying drawing, forming a part thereof.

Figure 3 is a side elevation of the faucet;
and

Figure 5 is a bottom view of the faucet.

I claim:

The ornamental design for a dispenser faucet as shown.
